Inventor:

Nathan H. Adams,
by *Alphonse S. Hunt*
His Attorney.

UNITED STATES PATENT OFFICE.

NATHAN H. ADAMS, OF SCHENECTADY, NEW YORK, ASSIGNOR TO GENERAL ELECTRIC COMPANY, A CORPORATION OF NEW YORK.

METHOD OF FABRICATING THERMOELECTRIC UNITS.

Application filed March 31, 1925. Serial No. 19,732.

My invention relates to thermo-electric units and more particularly to a method of fabricating a multi-unit thermopile.

It is an object of my invention to provide a method of fabricating a compact thermopile which will permit quantity production of thermopiles at a minimum expense.

Hitherto, thermopiles have been constructed and assembled in such a crude and laborious manner as to preclude their manufacture on a commercial scale. In the present application as well as in my copending application Serial No. 19,733 filed March 31, 1925, I have disclosed a type of thermopile adapted for use in operating small electrical apparatus, such as the space current devices used in radio broadcast reception. For a device of this character to become a commercial possibility, it is obviously not only necessary that it should be capable of quantity production, but that the cost of production should be relatively small. With the method of fabrication disclosed in the present application it is possible to construct at reasonable cost a compact thermopile having a relatively large number of couples and adapted for the purpose above specified.

The novel features of my invention which I believe to be characteristic are set forth with particularity in the appended claims. My invention itself, however, will best be understood by reference to the following description taken in connection with the following drawing in which Figs. 1 and 5 show plan views of stacks of sheets of thermo-electric metal and the lines on which the metal may be cut; Fig. 2 shows diagrammatically the manner in which the successive sheets are joined; Fig. 3 is a perspective view of a portion of a completed thermopile; Fig. 4 is a plan view of a plurality of thermo-piles arranged about a central heating element; Fig. 6 is an exploded view of a preferred form of thermo-electric generator; Fig. 7 is a perspective view of a portion of a thermo-pile and cooling means therefor; Fig. 8 shows a plan view of a plurality of sheets of thermo-electric metal with a line weld extending centrally and lengthwise of the metal sheets.

In carrying my method of fabrication into effect, I superpose two sheets, 1 and 2, of dissimilar metals such as nickel-chromium and copper-nickel and line weld them upon their

flat surfaces and near their edges as shown 55 at 3. Successive unlike metal sheets are then added to the first two sheets and in turn line welded as at 4 and 5 to form an integral zig-zag strip of any number of elements desired. When the strip contains the 60 desired number of elements it is compressed and cut along the dotted lines 6, transverse to the line of weld, to form a plurality of thermo-pile units. Any suitable insulation means such as mica or the like may then be 65 inserted between the several metal plates comprising the thermo-piles as shown at 8 and 9 and the units assembled around a central heater 10 as shown in Fig. 4.

In the preferred embodiment of my invention as shown in Fig. 6 the successive unlike thermo-electric metal sheets are assembled and line welded on their flat surfaces and along their edges to form a zig-zag strip as set forth in connection with 70 Figs. 2 and 3. The metal sheets forming the zig-zag strip are then compressed and cut along lines 11 transverse to the line of weld to form a series of thermopile units 12, the individual metal plates or members of 75 the units being rectangular in shape. Each unit is then placed in a clamp or jig while a slot or groove 13 is machined in the welded portion of the unit, which comprises the junction to be heated. These junctions will 80 hereinafter be referred to as the "hot junctions". Additional slots or grooves 14 and 15 are machined in each side of the unit adjacent the hot junction to provide relatively small connecting portions between the 85 hot junctions of the pile and the main body portion of the pile. Mica or other suitable insulation is then inserted between the different elements of the pile as in Fig. 3 and the units assembled with their slotted or 90 grooved portions in opposition so as to substantially surround a central insulated heater element 16 which closely fits within the grooved portions. By assembling, line 95 welding and cutting the metal sheets as shown, it is possible to quickly produce a large quantity of thermopiles with a minimum expenditure of time and at a relatively low cost.

By the provision of a slot or groove in the 100 end portion of the thermopiles which includes the hot junctions, I obtain a relatively large heat receiving surface which sub-

stantially surrounds and is closely associated with the heating element. Grooves 14 and 15, which are cut in the sides of the thermopiles adjacent the hot junctions, retard the flow of heat toward the cold junctions. Since, however, a thermo-electric generator operates at its highest efficiency when the internal resistance of the generator is substantially equal to the resistance of the external load circuit supplied by the generator, the extent of grooves 14 and 15 is necessarily governed by a consideration of the total internal resistance of the thermopiles and of the load to be supplied by the thermo-electric generator.

An electrical insulator 18, which may be a thin sheet of mica, is inserted between the heater 16 and the heat receiving surface 13. Leads 17 which are connected to the ends of the thermopiles may be arranged to connect the thermopiles in parallel or series as desired.

Under certain circumstances I may desire to provide a cooling means integral with the thermopiles. Such an arrangement is shown in Fig. 7. In this case two unlike metal sheets are superposed and line welded along their flat surfaces and near their edges as before. The sheets are then cut transverse to the line of weld to form a plurality of V-shaped sections 19. Two V sections are then superposed so that unlike metal plates will be adjacent and in parallel relation to each other, and the welded portion of one section will be directly above the welded portion of the second section. A cooling fin 20, of copper or any suitable metal, is then inserted between the free ends of the two parallel plates which will comprise a cold junction of the thermopile and the fin and plates line welded or permanently united in any suitable manner. Additional V-shaped sections and cooling fins may be added to the first two sections until the desired number of elements is contained in the thermopile unit. The units are then clamped as before while grooves are machined in the end including the hot junctions and in the sides of the thermopile adjacent the hot junctions. Mica or similar insulation is then inserted as before between the individual members of the thermopile.

I have indicated in Fig. 8 a third method of fabricating a thermopile. In this arrangement two sheets of unlike metal 21, having a width double that required for the length of each element of a thermopile, are superposed as in the preceding cases. A line weld is then made centrally and lengthwise of the sheets as indicated at 22 and the two sheets are then cut along the dotted line 23. The welded V-shaped portions are then cut transverse to the line of weld to provide a plurality of thermopile sections which are

superposed successively to form the desired number of sections in the thermopile. The welded portions comprise the hot junctions of the thermopile to be fabricated. The cold junctions may be united to form a zig-zag strip, as shown in Fig. 2, by means of a line weld or if desired, the different sheets may be electroplated, the pile placed in a jig, pressure applied, and the ends permanently united by placing the pile in a suitable heated furnace. The free ends or cold junctions might also, if desired, be permanently connected by electroplating the cold junctions with a brazing material such as silver or spelter and then applying a heavy current to the cold junctions whereby a resistance weld may be obtained. When the zig-zag strip has been formed grooves are machined in the end and sides of each section as in Fig. 6. It will be apparent that various methods of joining the free ends or cold junctions may be employed without departing from the scope of my invention set forth in the appended claims.

What I claim as new and desire to secure by Letters Patent of the United States is:

1. The method of fabricating thermo-electric units which comprises superposing sheets of unlike metal, line welding said sheets and subdividing said sheets transverse to the line of weld.
2. The method of fabricating a thermo-electric unit which comprises superposing two sheets of unlike metals, line welding the sheets and cutting a slot in the welded portion of said sheets.
3. The method of fabricating a thermo-electric unit which comprises assembling and line welding successive unlike sheets of metal to form a zig-zag strip.
4. The method of fabricating a thermo-electric unit which comprises assembling and line welding successive unlike sheets of metal to form a zig-zag strip and cutting the strip transverse to the line of weld.
5. The method of fabricating a thermo-electric unit which comprises assembling and line welding successive unlike sheets of metal to form a zig-zag strip and cutting the strip transverse to the line of weld to provide a plurality of units and cutting a slot in one side of one of said units.
6. The method of fabricating a thermo-electric unit which comprises assembling and line welding successive unlike sheets of metal to form a zig-zag strip, cutting the strip transverse to the line of weld to provide a plurality of units and cutting a slot in a welded portion of a unit.
7. The method of fabricating a thermo-electric unit which comprises assembling and line welding successive unlike sheets of metal to form a zig-zag strip, cutting the strip transverse to the line of welding to provide a plurality of units and cutting a

slot in a welded portion of a unit and another slot in one side of said unit adjacent said first slot.

8. The method of fabricating a thermoelectric device which comprises assembling and line welding successive sheets of unlike metal to form a zig-zag strip, cutting said strip transverse to said line of weld to provide a plurality of units and assembling said units about an interposed heater.

9. The method of fabricating a thermoelectric device which comprises assembling and welding successive sheets of unlike metal to form a zig-zag strip, cutting said strip to provide a plurality of units each unit including a plurality of hot junctions, cutting a slot in that portion of each unit including the hot junctions and assembling said units with their slotted portions in opposition.

10. The method of fabricating a thermoelectric unit which comprises uniting a plurality of unlike metal plates to form a ther-

mopile including a plurality of hot junctions, and forming a slot in that portion of the thermopile including the hot junctions. 25

11. The method of fabricating a thermoelectric unit which comprises uniting a plurality of unlike metal plates to form a thermopile including a plurality of hot junctions, cutting a slot in that portion of the thermopile including the hot junctions and cutting another slot in the thermopile adjacent the hot junctions. 30

12. The method of fabricating a thermoelectric unit which comprises uniting a plurality of unlike metal plates to form a thermopile including a plurality of hot junctions, cutting a slot in that portion of the thermopile comprising the hot junctions and inserting a heater element in said slot. 35 40

In witness whereof, I have hereunto set my hand this 30th day of March 1925.

NATHAN H. ADAMS.
